UNITED STATES PATENT OFFICE.

MIRIAM GROSS, OF CHICAGO, ILLINOIS.

DESIGN FOR A DRESS.

Application filed March 12, 1925. Serial No. 12,690. Term of patent 14 years.

To all whom it may concern:

Be it known that I, MIRIAM GROSS, a citizen of the United States, residing at Chicago, in the county of Cook and State of Illinois, have invented a new, original, and ornamental Design for Dress, of which the following is a specification, reference being had to the accompanying drawing, forming part thereof, in which I wish particularly to refer to the bottom border, the shoulders, and sleeves of the dress, which are in the purl stitch. This feature is in aesthetic con-

trast to the artistic arrangement of purl and knit squares appearing in the body of the dress.

Figure 1 is a front view of a dress, showing my new design. Figure 2 is a more detailed view of the appearance of the purl and the knit stitches.

I claim:

The ornamental design for a dress, substantially as shown and described.

MIRIAM GROSS.
